UNITED STATES PATENT OFFICE.

HARRY M. POPE, OF HARTFORD, CONNECTICUT, ASSIGNOR TO THE COLUMBIA AND ELECTRIC VEHICLE COMPANY, OF SAME PLACE AND JERSEY CITY, NEW JERSEY.

DESIGN FOR A RUNNING-FRAME FOR VEHICLES.

SPECIFICATION forming part of Design No. 31,981, dated December 12, 1899.

Application filed November 1, 1899. Serial No. 735,639. Term of patent 14 years.

To all whom it may concern:

Be it known that I, HARRY M. POPE, a citizen of the United States, residing in the city of Hartford, county of Hartford, State of Connecticut, have invented and produced a certain new and original Design for Running-Frames for Vehicles, of which the following is a specification, reference being had to the accompanying drawings, forming a part hereof.

10 This invention relates to that portion of a vehicle which is intermediate the wheels and is generally known as a "running-frame;" and it consists in the novel shape or form thereof, as herein set forth.

15 In the drawings, Figure 1 represents a plan of the running-frame which embodies my design. Fig. 2 is a side elevation of the same.

The essential feature of my design is the substantially triangular outline of the main 20 portion as bounded by the side members and an imaginary line connecting their diverging ends, with the apex of the triangle

joining a transverse front member near its middle.

As seen in plan, the frame presents one portion A, which is in appearance a triangle, and a second portion B, which is a cross member united thereto at the apex of the triangle. The transverse portion B has at its ends two perforated cross members b', while the other 25 portion A consists of members a a', which are tied together intermediate their ends by a cross member c. Near the junction with B the members a a' merge into a member d, through which they are united with B. 30

I claim as my invention—

The design for a running-frame for vehicles, substantially as shown and described.

This specification signed and witnessed this 30th day of October, A. D. 1899.

HARRY M. POPE.

In presence of—

H. L. HART,
HERMANN F. CUNTZ.
